CLAIM

I claim the ornamental design for a cork extractor, as shown.

DESCRIPTION

FIG. 1—is a perspective view of a cork extractor showing my new design.

FIG. 2—is a top view thereof.

FIG. 3—is a side elevational view thereof.

FIG. 4—is a front elevational view thereof.

FIG. 5—is a side elevational view showing the opposite side of FIG. 3.

FIG. 6—is a bottom view thereof; and,

FIG. 7—is a rear view thereof.
